MESNE ASSIGNMENTS, TO THE GARDNER-DENVER COMPANY, OF QUINCY, ILLINOIS, A CORPORATION OF DELAWARE.

OIL CHECK FOR STOPERS.

Application filed April 14, 1920. Serial No. 373,897.

In drilling apparatus, having fluid actuated means for feeding the drilling mechanism to and maintaining it against the work, it sometimes happens that the machine will slip and occasionally the drill steel will break. As a consequence, the feeding means, being relieved from resistance to its movement, will be suddenly extended by the motive fluid therein and the drill runner or operator is apt to be seriously injured as a result.

The primary object of the present invention is to provide a brake for the feeding means, whereby the speed of its movement is limited, and the danger of mishap thereby minimized.

A further and important object is to provide means whereby the movement of the feeding means is under the control of the operator, and this control is independent of the control of the motive fluid to the feeding means.

While the invention is particularly useful in connection with drilling apparatus, it may be employed for other purposes of an analogous character.

An embodiment of the invention that is at present considered the preferable one, is illustrated in the accompanying drawings, wherein:

Figure 1 is a longitudinal sectional view through the feeding means of a drilling machine illustrating the novel control mechanism.

Figure 2 is a detail sectional view on an enlarged scale of the controlling or brake piston.

Figure 3 is a detail view on an enlarged scale through the head block.

Figure 4 is a cross sectional view on the line 4-4 of Figure 3.

Figure 5 is a detail view of the check controlling valve, showing the same in its open or supply position.

In the structure disclosed a head block 6 is provided, on the front side of which is mounted a drill or tool actuating motor, which may be of any well known or desired construction, as will be evident to those skilled in the art. Thus a portion of the cylinder of such tool actuating motor is shown at 7, and located therein is a reciprocating piston 8 that operates on the drill steel or other tool. The head block is provided on one side with an enlargement 9 terminat-

ing in a coupling nipple 10, as shown in Figure 4, to which the supply hose line may be connected. In the enlargement is located a rotary throttle valve 11 having a bore 12 and a lateral port 13 that is movable into and out of communication with the inlet end 14 of a passageway 14 that supplies motive fluid to the drill actuating motor. The head 6 is provided on its side opposite to the enlargement 9 with a socket 15 in which is fixed a handle 16 by which the machine is turned during the drilling operation.

Mounted on the rear side of the head block 6 is fluid actuated feeding means preferably constructed as follows. A cylinder member 17 is clamped against the rear side of the head block by means of a collar 18 in a manner well understood, and held between adjacent portions of the cylinder member 17 and head block 6 is a plug 19. A piston member is mounted to reciprocate within the cylinder member, and comprises a head 20 carrying a packing cup 21 on its inner side and having a tubular extension 22 threaded to its outer side and adapted to slide through a head sleeve 23 on the outer end of the cylinder 17. The extension 22 terminates in a closure cap 24 carrying a spur 25. The throttle valve 11 is provided with a lateral port 26 that is movable into and out of communication with a passageway 27 in the head block, said passageway having communication with an annular groove 28 formed in the head block and closed by the plug 19. From this groove a port 29 opens into the inner end of the cylinder member. Thus, means are provided for admitting fluid under pressure to the inner end of the cylinder member, to effect the extension of the feeding means by forcing the piston 20 outwardly or moving the cylinder of the tool actuating motor upwardly. The admission of the motive fluid, it will be obvious, is controlled by the throttle valve 11, and said throttle valve is also provided with an external groove 30 adapted to afford communication between the passageway 27 and an exhaust port 31 in the enlargement 9, when the supply port 26 is out of communication with said passageway 27. Thus the motive fluid can be permitted to escape from the cylinder member for the purpose of contracting the feeding means.

The tubular extension 22 of the piston member constitutes a cylinder in which is located

a piston 32 having at its inner end a packing cup 33, and also provided at its outer end with a reduced extension 34. This piston is fixed with relation to the cylinder 17 and the head block 6. To this end, it is connected by a piston rod 35 with the plug 19, the ends of said rod being respectively threaded into the piston 32 and the said plug 19. This piston 32 thus subdivides the interior of the extension or cylinder 22 into two chambers 36 and 37. Communication is afforded between the two chambers 36 and 37 by a passageway having a rear portion 38 extending centrally through the extension 34 of the piston, and having branches 39 through the piston head and opening into the chamber 36. Supplemental passageways 40 are also formed in the extension 34 of the piston on opposite sides of the passageway 38 and communicate with the branches 39. These passageways 40 are controlled by inwardly opening check valves 41 located therein.

The passageway 38 is provided with a valve seat 42, and cooperating therewith is a plunger valve 43 normally held in open position by a coiled spring 44 operating thereagainst. At the inner end of the plunger valve and housed within the piston 32 are spaced diaphragms 45 and 46, one of which is adapted to bear against the inner end of the plunger valve. A plunger button 47 is interposed between the diaphragms.

Means are provided for directing fluid under pressure against the inner face of the diaphragm 46, this means being under the control of the drill runner or operator. For this purpose, the annular groove 28 in the rear face of the head block 6, and which is in communication with the supply passageway 27, as above explained, has communication through a passageway 48 with a peripheral groove 49 formed in the portion of the handle 16 that is in the socket 15. The groove 49 is in communication with a chamber 50 in the handle by means of a port 51. Another port 52, communicating with the chamber 50, is in communication with another annular groove 53 in the handle 16, and the groove 53 is connected to another annular groove 54, in the rear face of the head block 6 by a passageway 55. These various connections are shown more particularly in Figures 1, 3 and 4. The annular groove 54 is in turn connected by a passageway 56 with a longitudinal bore 57 in the piston rod 35, and this bore 57 opens into a chamber 58, the rear wall of which is the diaphragm 46.

Communication between the ports 51 and 52 through the chamber 50 in the handle 16 is controlled by a valve 59 in said chamber operating against a valve seat 60 formed between the two parts 51 and 52. The valve 59 is normally held to its seat by a spring 61 in the chamber 60 operating against said valve. The valve 59 has a stem 62 that projects into

a bore 63 formed in the outer portion of the handle 16, and an actuating lever 64, pivoted as shown at 65 on the handle, is mounted in a slot 66 formed in said handle and has an inwardly extending lug 67 that bears against the outer end of the valve stem. The outward movement of the lever 64 is limited by a lug 68 on the free end thereof, and adapted to engage the adjacent wall of the handle. Said lever has an outstanding enlargement 69 constituting a projection that can be pressed upon by the operator. The stem 62 of the valve furthermore has a longitudinal bore 70 opening through its outer end, and communicating at its inner end with an annular groove 71 formed in said stem, this groove being movable into and out of register with a port 72 that communicates with the groove 53.

The operation is as follows. A body of oil is placed within the piston extension 32, and when the parts are in the position shown in Figure 1, oil will be in the chamber 36 between the pistons 20 and 32. If now, the throttle valve 11 is turned to admit fluid under pressure to the motor, to operate the same the port 26 is brought into register with the port 27, and motive fluid will thus enter the inner end of the cylinder 17 and operate against the piston 20. As the spur 25 is against a suitable support, it will be evident that the cylinder will move outwardly. The rate of movement, however, is determined by the displacement of the oil, which passes through the restricted passageway 38 into the chamber 37. Thus, it will be evident that this oil will constitute a resistance to the free movement of the piston, and consequently if the apparatus is suddenly relieved from resistance, as by the breaking of a drill steel, the motive fluid will not suddenly extend the feeding means to its full length, inasmuch as the oil must first pass through the relatively small orifice 38. On the other hand, if the motive fluid is cut off from the feeding means, the piston can be quickly retracted within the cylinder, inasmuch as the supplemental passages 40 will permit a greater flow in the reverse direction, these passages being closed during the working or extension movement by the valves 41.

As long as the controlling valve 59 in the handle 63 is closed, the chamber 58 will be open to atmosphere through the passage 57, port 56, channel 54, passageway 55, groove 53, port 72 and passageway 70. The plug valve 43 is thus held in open position by the spring 44. If, however, the operator desires to stop the feed of the apparatus for any reason, he has only to press upon the extending portion 69 of the lever 64. This opens the valve 59, and closes the exhaust passage 70 by moving the groove 71 out of register with the port 72, as illustrated in Figure 3. Motive fluid under pressure then flows from the groove 28 through the chamber 50 past the valve 59, and through the port 55, the chan-

nel 54, port 56, and through the port 55, the channel 54, port 56 and passageway 57 into the chamber 58. This acting against the diaphragm 46 will press the body 47 rearwardly and the latter acting on the diaphragm 45 will cause the same to move the plug 43 to its closed position against the action of the spring 44. It will be obvious therefore that no oil can flow through the restricted passageway 38 and the feeding means will be brought to a standstill.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described our invention, what we claim as new, and desire to secure by Letters Patent, is:—

25. 1. In apparatus of the character set forth, the combination with a tool-actuating motor, of fluid operated feeding means for the motor comprising a cylinder member, a piston member operating therein, means for introducing fluid under pressure into the cylinder member to act against the piston member, spaced chambers within the piston member, a partition separating the chambers and fixed with respect to the cylinder member, and a restricted passageway affording communication between the chambers.
2. In apparatus of the character set forth, the combination with a tool-actuating motor, of fluid operated feeding means therefor, comprising a cylinder member and pistons therein that are relatively movable with respect to each other, means for introducing fluid under pressure into the cylinder member and against one of the pistons to effect the feeding movement of the feeding means, and means for maintaining a displaceable resistant body against the other of the pistons to govern the speed of such feeding movement.
3. In apparatus of the character set forth, the combination with a tool-actuating motor, of fluid operated feeding means therefor comprising a cylinder member and pistons therein that are relatively movable with respect to each other, means for introducing fluid under pressure into the cylinder member and against one of the pistons to effect the feeding movement of the feeding means, and means for maintaining a displaceable resistant body between the two relatively movable pistons to govern the speed of such feeding movement.
4. In apparatus of the character set forth, the combination with a tool-actuating motor, of fluid operated feeding means including a

cylinder member connected to the motor, a piston member movably mounted in the cylinder member and comprising a head having a tubular extension that projects therefrom, means for introducing fluid under pressure into the cylinder against the head, a piston within the tubular extension fixed with relation to the cylinder member and subdividing the interior of said extension into a plurality of chambers, and a restricted passageway through the piston affording communication between the chambers.

5. In apparatus of the character set forth, the combination with a tool-actuating motor having a rear head block, of fluid operated feeding means including a cylinder member connected to the rear head block, a piston member movably mounted in the cylinder member and comprising a head having a tubular extension that projects therefrom, means for introducing fluid under pressure into the cylinder against the head, a piston within the tubular extension and having a rod extending through the head of the piston member and connected to the head block, said piston subdividing the interior of said extension into a plurality of chambers, and a restricted passageway through the piston affording communication between the chambers.

6. In apparatus of the character set forth, the combination with a tool-actuating motor, of fluid operated feeding means for the motor comprising a cylinder member, a tubular piston member operating therein, means for introducing fluid under pressure into the cylinder member to act against the piston member, spaced chambers within the piston member, a partition separating the chambers and fixed with respect to the cylinder member, a restricted passageway affording communication between the chambers, a supplemental passageway between the chambers, and a check valve controlling the latter passageway.

7. In apparatus of the character set forth, the combination with a tool-actuating motor, of fluid operated feeding means including a cylinder member connected to the motor, a piston member movably mounted in the cylinder member and comprising a head having a tubular extension that projects therefrom, means for introducing fluid under pressure into the cylinder member against the head, a piston within the tubular extension fixed with relation to the cylinder member and subdividing the interior of said extension into a plurality of chambers, a restricted passageway through the piston affording communication between the chambers, a supplemental return passageway in the piston, and a check valve controlling the latter passageway.

8. In apparatus of the character set forth, the combination with a tool-actuating motor, of fluid operated feeding means for

- the motor, means for admitting fluid under pressure to the feeding means and controlling the supply thereof, a handle for rotating the tool-actuating motor, normally inactive means for governing the movement of the feeding means by the fluid and means for causing said means to become active including a manually operated controlling device on said handle.
9. In apparatus of the character set forth, the combination with a tool-actuating motor, of fluid operated feeding means for the motor comprising a cylinder member, a piston member operating therein, means for introducing fluid under pressure into the cylinder member to act against the piston member, spaced chambers within the piston member, a partition separating the chambers and fixed with respect to the cylinder member, a restricted passageway affording communication between the chambers, a valve controlling the passageway, and manually controlled means for actuating the valve.
10. In apparatus of the character set forth, the combination with a tool-actuating motor, of fluid operated feeding means including a cylinder member connected to the motor, a piston member movably mounted in the cylinder member and comprising a head having a tubular extension that projects therefrom, means for introducing fluid under pressure into the cylinder against the head, a piston within the tubular extension fixed with relation to the cylinder member and subdividing the interior of said extension into a plurality of chambers, a restricted passageway through the piston affording communication between the chambers, a valve controlling the restricted passageway, and means for moving the valve.
11. In apparatus of the character set forth, the combination with a tool-actuating motor, of fluid operated feeding means including a cylinder member connected to the motor, a piston member normally mounted in the cylinder member and comprising a head having a tubular extension that projects therefrom, means for introducing fluid under pressure into the cylinder against the head, a piston within the tubular extension fixed with relation to the cylinder member and subdividing the interior of said extension into a plurality of chambers, a restricted passageway through the piston affording communication between the chambers, a valve controlling the restricted passageway, fluid actuated means for moving the valve, and a manual device for controlling the action of the fluid actuated means.
12. In apparatus of the character set forth, the combination with a tool-actuating motor, of fluid operated feeding means including a cylinder member connected to the motor, a piston member normally mounted in the cylinder member and comprising a head having a tubular extension that projects therefrom, means for introducing fluid under pressure into the cylinder against the head, a piston within the tubular extension fixed with relation to the cylinder member and subdividing the interior of said extension into a plurality of chambers, a restricted passageway through the piston affording communication between the chambers, a valve controlling the restricted passageway, fluid actuated means for introducing fluid under pressure into the cylinder against the head, a piston within the tubular extension fixed with relation to the cylinder member and subdividing the interior of said extension into a plurality of chambers, a restricted passageway through the piston affording communication between the chambers, a valve controlling the restricted passageway, a handle for rotating the tool-actuating motor, and means on the handle for controlling the movement of the valve.
13. In apparatus of the character set forth, the combination with a tool-actuating motor, of fluid operated feeding means including a cylinder member connected to the motor, a piston member movably mounted in the cylinder member and comprising a head having a tubular extension that projects therefrom, means for introducing fluid under pressure into the cylinder against the head, a piston within the tubular extension fixed with relation to the cylinder member and subdividing the interior of said extension into a plurality of chambers, a restricted passageway through the piston affording communication between the chambers, a valve controlling the restricted passageway, a handle for rotating the tool-actuating motor, and means on the handle for controlling the movement of the valve.
14. In apparatus of the character set forth, the combination with a tool-actuating motor having a rear head block, of fluid operated feeding means including a cylinder member connected to the rear head block, a piston member movably mounted in the cylinder member and comprising a head having a tubular extension that projects therefrom, means for introducing fluid under pressure into the cylinder against the head, a piston within the tubular extension and having a rod extending through the head of the piston member and connected to the head block, said piston subdividing the interior of said extension into a plurality of chambers, a restricted passageway through the piston affording communication between the chambers, a valve controlling the restricted passageway, fluid actuated means in the piston for operating the valve, and means for supplying fluid under pressure to the rod to operate the fluid actuated means.
15. In apparatus of the character set forth, the combination with a tool-actuating motor having a rear head block, of fluid operated feeding means including a cylinder member connected to the rear head block, a piston member movably mounted in the cylinder member and comprising a head having a tubular extension that projects therefrom, means for introducing fluid under pressure into the cylinder against the head, a piston within the tubular extension fixed with relation to the cylinder member and subdividing the interior of said extension into a plurality of chambers, a restricted passageway through the piston affording communication between the chambers, a valve controlling the restricted passageway, fluid actuated means in the piston for operating the valve, and means for supplying fluid under pressure to the rod to operate the fluid actuated means.

within the tubular extension and having a rod extending through the head of the piston member and connected to the head block, said piston subdividing the interior of said extension into a plurality of chambers, a restricted passageway through the piston affording communication between the chambers, a valve controlling the restricted passageway, a handle for turning the tool actuating motor, fluid actuated means in the piston for moving the valve, a passageway for supplying fluid under pressure to the fluid actuated means, said passageway extending through the head, the handle and rod, and a controlling valve for said passageway in the handle.

16. In apparatus of the character set forth, the combination with a tool actuating motor, of fluid operated feeding means therefor, comprising a cylinder member and a tubular piston member located in the cylinder member and itself constituting a cylinder, a piston within the piston member and fixed with relation to the cylinder member, and means for permitting the passage of fluid from one side of the latter piston to the other within the piston member.

17. In apparatus of the character set forth, the combination with a tool actuating motor, of fluid operated feeding means therefor, comprising a cylinder member and a tubular piston member located in the cylinder member, and itself constituting a cylinder, a piston within the piston member and fixed with relation to the cylinder member, means for permitting the passage of fluid from one side of the latter piston to the other within the piston member, and manual means for controlling such passage.

18. In apparatus of the character set forth, the combination with a tool actuated motor, of fluid operated feeding means therefor, a fluid check for the feeding means that permits its slow continuous movement, and associated handles for holding the tool actuating motor and for controlling the fluid check to stop the feed of said motor.

19. In apparatus of the character set forth, the combination with work performing means, a fluid operated feeding means therefor including relatively reciprocable telescoping tubular members, correspondingly relatively movable heads within the tubular member, means for admitting motive fluid against one of the heads for effecting the relative movement of said heads and tubular members, a body of displaceable fluid confined by and between the heads, means for permitting the escape of said fluid when the heads relatively move toward each other, and means for receiving and holding the escaping fluid within the feeding means.

20. In apparatus of the character set forth, the combination with work performing means, of fluid operated feeding means therefor including a cylinder member, a tubular

member slidably engaged therewith and having a portion that projects from one end thereof, relatively movable heads providing a variable chamber within the tubular member, a displaceable fluid in said member, means for permitting the displacement of the fluid when the chamber is contracted by the approach of the heads one to the other, and means for directing motive fluid against one of the heads to effect their relative movement and the projection of the tubular member.

21. In apparatus of the character set forth, the combination with work performing means, of fluid operated feeding means therefor including a cylinder member, a tubular member slidably engaged therewith and having a portion that projects from one end thereof, a head fixed to the tubular member, a head fixed with respect to the cylinder member, said heads forming between them and in the tubular member a variable chamber, a displaceable fluid in said chamber, means for permitting the displacement of the fluid past one of the heads when the chamber is contracted by the approach of the heads one to the other, and means for directing motive fluid against one of the heads to effect their relative movement and the projection of the tubular member.

22. In apparatus of the character set forth, the combination with a tool operating motor, of a cylinder member connected to its rear end, a piston comprising a tubular member slidably mounted in the cylinder member and adapted to be projected from its rear end, and a head fixed to the inner end of the tubular member, a second head located within the tubular member, a rod extending through the first head and secured to the second head for holding it, said heads forming a variable chamber between them and in the tubular member, means for permitting the passage of the fluid to and from said chamber past one of the heads, and means for applying fluid under pressure against the other head to cause the relative movements of the cylinder member and the piston.

23. In apparatus of the character set forth, the combination with a tool operating motor, of extensible feeding means therefor connected to its rear end and disposed longitudinally thereof, said feeding means comprising a cylinder member and a piston member operating in the cylinder member, one of said members being connected to the tool, the piston member including a head operating in the cylinder member, means for directing motive fluid to the cylinder member, and against one side of the head to effect the relative movement of the cylinder member and piston member to extend the feeding means, a displaceable resistant body of liquid within the piston member and against the other side of the head, a chamber within the cylinder member.

- der member for receiving the liquid when displaced, and means for permitting the liquid to flow into said member as it is displaced by the head and permitting its return on the retrograde movement of the head.
24. In apparatus of the character set forth, the combination with a tool actuating motor, of extensible fluid operated feeding means therefor connected to its rear end, a head interposed between the tool and feeding means, a fluid check means comprising a liq-

uid circulatory system located within the extensible feeding means for permitting the latter's slow continuous extension and preventing its unduly rapid continuous extension; and projecting handles mounted on the back head, one for holding the tool and one for controlling the circulation of the liquid.

In testimony whereof, we affix our signatures.

GEORGE A. SHAW.
JOHN L. BARRA.
